United States Patent Office

Des. 222,877
Patented Jan. 25, 1972

222,877

DOOR LEVER

John R. Gerlach, Monterey Park, Calif., assignor to
Emhart Corporation, Bloomfield, Conn.

Filed July 29, 1970, Ser. No. 24,200

Term of patent 14 years

Int. Cl. D8—07

U.S. Cl. D8—162

FIG. 1.

FIG. 2.

FIG. 3.

FIG. 4.

FIG. 5.

FIG. 1 is a front elevational view of the design for a door lever;

FIG. 2 is a rear elevational view thereof;

FIG. 3 is a top plan view thereof, the bottom plan view thereof being identical;

FIG. 4 is a left end view thereof;

FIG. 5 is a right end view thereof.

I claim:

The ornamental design for a door lever, as shown and described.
